DESANDER OR VACUUM BAILER

Allen H. Fletcher, Bakersfield, Calif.

Application June 27, 1933, Serial No. 677,941

7 Claims. (Cl. 166—19)

This invention relates to improvements in desanding or bailing devices for oil wells and pertains particularly to a device of this character which is vacuum operated.

5 The primary object of the present invention is to provide a desander or bailer for oil wells in which two relatively movable parts coact to create a vacuum in the bailer which effectively draws the sand thereinto from the bottom of 10 the well.

Another object of the invention is to provide a desander or bailer in which a vacuum action is established for drawing in the sand and means is provided whereby the vacuum will be broken 15 suddenly so that rapid relative movement between two of the parts will take place to produce a jarring action by which the sand will be caused to effectively close an inlet valve of the device.

20 The invention will be best understood from a consideration of the following detailed description taken in connection with the accompanying drawing forming part of this specification, with the understanding, however, that the invention 25 is not confined to any strict conformity with the showing of the drawing but may be changed or modified so long as such changes or modifications mark no material departure from the salient features of the invention as expressed in 30 the appended claims.

In the drawing:—

Figure 1 is a view in longitudinal section through the bailer or desander embodying the present invention;

35 Figure 2 is a sectional view taken substantially upon the line 2—2 of Figure 1;

Figure 3 is a sectional view taken substantially upon the line 3—3 of Figure 1.

Referring now more particularly to the drawing wherein like numerals of reference indicate corresponding parts throughout the several views, the numeral 1 indicates the usual bottom or shoe for devices of this character. The upper end of this shoe which is reduced in diameter and screw-threaded as indicated at 2 has threadably coupled therewith the tubular portion 3, the lower end of which is interiorly threaded to receive the extension 2 of the shoe, while the upper end is reduced and exteriorly 45 threaded as indicated at 4 to receive the lower end of the relatively long intermediate pipe portion 5.

The short tubular portion 3 which connects the shoe with the pipe portion 5 is of slightly 55 less exterior diameter than the shoe and pipe

and is surrounded by the sleeve 6, the outer surface of which is flush with the outer surfaces of the shoe and pipe 5. This sleeve 6 is rotatable about the tubular portion 3 and has a series of openings 7 formed therein which are 60 designed to be brought into registration with the ports 8 in the wall of the portion 3 to facilitate the discharge of sand from the bailer.

Secured between the tubular portion 3 and the upper end of the shoe 1 is an upwardly or 65 inwardly opening valve unit 9 by means of which sand is retained in the bailer, as will be hereinafter more fully described.

Threadably secured to the reduced portion 10 of the upper end of the pipe or body 5 is a packing carrying collar 11. This collar is formed to provide the two interior shoulders 12 and 13, the first of which is directed upwardly, while the other is directed downwardly and has a portion in contact with the upper end of the 70 pipe body 5. Upon the upper shoulder 12 of the collar 11 is a packing 14 which is retained in place by the gland nut 15 and this in turn is locked in position by the surrounding lock nut 16 which is threaded thereon.

Extending through the packing collar into the body 5 is the hollow or tubular piston 17, the lower end of which is open, while the upper end has a head 18 in the center of which is formed 75 the relatively small opening 19.

At a point a substantial distance inwardly of the lower end of the piston 17 there is formed a port 20 and below this port and in relatively close proximity to the lower end of the piston 80 is a second port 21.

Upon a circumferential line on the piston 7 adjacent the port 21 are secured shock shoulders 22 which, when the piston 7 is drawn upwardly, are designed to abut the shoulder 13 of the packing collar.

Upon the upper end of the piston 17 there is secured the hollow head 23, the connection with the piston being made by the threaded sleeve 24. The upper end of this head 23 is formed in any suitable manner to facilitate the attachment of a cable thereto and the head constitutes a housing or chamber for a ball 25 which normally seats in the opening 19 to close the same. The head 23 is also provided with air or relief ports 26, the purpose of which will become apparent in the description of the operation of the device.

Surrounding the upper end of the piston 17 and disposed between the gland nut 15 and the sleeve 24 is a shock absorbing spring 27 which 110

prevents the sleeve 24 from coming into contact with the gland nut when the piston is moved into the pipe or barrel 5.

In the operation of the present bailer or de-sander the sleeve 6 is turned to bring the openings 7 and 8 out of registry and thus close the lower part of the barrel. The tool is then lowered into the well by means of a cable attached to the upper end of the head 23 and the sharpened lower edge of the shoe 1 will cut down into the sand which has collected in the bottom of the well. By then drawing up upon the cable the piston 17 will be drawn out from the barrel and will thus create a reduced pressure therein which will result in the sucking of the sand up through the valve 9 into the barrel. As the piston continues to be drawn outwardly it will reach the point where the port 20 will pass the packing 14, thus permitting air to enter the barrel and equalize the interior and exterior pressures. This sudden release of the reduced interior pressure will permit the piston and barrel to quickly or suddenly separate and will bring the lugs 22 into violent contact with the shoulder 13, thus producing a jarring which will jar loose the lower section of the bailer from the sand in which it is embedded and prevent the bailer from filling any further in case the lower section should be fast in the sand. By this means if the first jar does not loosen the lower part of the bailer the piston can be dropped slightly and then again raised to produce a suction and to again produce a jarring action, the hole 26 allowing the escape of air from the inside of the tool when the piston is lowered and also when the tool is first dropped into the hole, also allowing the escape of any fluid or gas which may enter the tool at the bottom of the hole. The port 21 above the lugs 22 permits any sand which may be in the upper part of the barrel to escape into the interior of the piston so that it will not interfere with the moving of the lugs and shoulder together.

After the tool has been removed from the well it may be readily emptied of the sand therein by bringing the openings 7 and 8 into registry and allowing the sand to flow out therethrough.

It will, of course, be readily apparent that the valve ball 25 remains seated during the period when the piston 17 is being drawn upwardly in the barrel but will be unseated when the piston is forced back down into the barrel, so that the air therein may escape.

Having thus described the invention, what is claimed is:—

1. An oil well bailer, comprising a barrel having an inlet valve at one end, a piston in the barrel and adapted to be drawn out therefrom through the other end to effect the production of a reduced pressure within the barrel, and means whereby the pressures within and outside of the barrel are equalized when the piston has reached a predetermined point in the barrel.

2. A well bailer, comprising a hollow body having an inlet valve, means for producing a reduced pressure within the body to effect the drawing of material thereinto through the valve, means for equalizing the pressures within and

exterior to the body, and means whereby the equalizing of such pressures will effect the jarring of the body.

3. A well bailer, comprising a barrel, an inlet valve at one end of the barrel, a piston reciprocable in the barrel and extending through the other end thereof whereby a reduced pressure is established in the barrel, said piston being of tubular formation and having an aperture in the wall thereof whereby air is permitted to enter the barrel when the port reaches one point therein, and means for coupling an operating cable with the piston.

4. A well bailer, comprising a barrel, an inlet valve at one end of the barrel, an elongated tubular piston reciprocably extending into the barrel through the other end, said piston having a port in the wall thereof, a packing surrounding the piston at the said other end of the barrel, and means for connecting an operating cable with the piston.

5. A well bailer, comprising a barrel, an inlet valve in one end of the barrel, a packing in the other end of the barrel, a tubular piston passing through the packing into the barrel and having a port in the wall thereof, means to provide an abutment shoulder inwardly of said packing, and means carried by the piston between the said port and the inner end thereof for contact with said shoulder to limit the outward movement of the piston after the port has passed the packing.

6. A well bailer, comprising a barrel, an inlet valve at one end of the barrel, a packing in the other end of the barrel, an elongated tubular piston passing through the packing into the barrel and having a port through its wall, a lug carried by the piston upon its outside surface and between said port and the inner end thereof, means in the barrel inwardly of the packing from the end adjacent thereto against which said lug abuts to limit the outward movement of the piston, said port being above the packing when the lug and said means are in contact, and a valve in the outer end of the piston which opens outwardly to permit air to escape from the piston when the latter is moved into the barrel.

7. A well bailer, comprising an elongated tubular body, a shoe at the lower end of said body, said body inwardly of said shoe having an opening in the wall thereof, an apertured sleeve surrounding the body and having an opening adapted to be brought into registry with the first opening, an inwardly opening valve between the said first opening and the shoe, a packing within the tubular body at the end remote from the shoe, a tubular piston extending through the packing into the tubular body and having a port in its wall, a lug carried by the piston between the port and the inner end thereof, a stop shoulder inwardly of said packing against which the lug engages to limit the outward movement of the piston, an outwardly opening valve at the outer end of the piston, and means facilitating the attachment of a cable with the outer end of the piston.
